JAMES LITTAUER ROYCOURT AND LEONARD HORINKO, OF NEW YORK, N. Y.

BELL.

1,076,606.

Specification of Letters Patent.

Patented Oct. 21, 1913.

Application filed March 21, 1913. Serial No. 755,857.

To all whom it may concern:

Be it known that we, JAMES LITTAUER ROYCOURT, a citizen of the United States, and LEONARD HORINKO, a subject of the 5 Czar of Russia, both residents of the city of New York, borough of Manhattan, in the county and State of New York, have invented a new and Improved Bell, of which the following is a full, clear, and exact description.

This invention relates to improvements in bells, and has for an object to provide an improved structure of simple strong construction with a minimum number of parts 15 and positive movement of the striking members upon the actuation of the operating button.

Another object of the invention is to form a bell with a push button and mechanical 20 movable striking means actuated in one direction by the push button and in the opposite direction by a suitable spring, so that a sound will be produced upon each movement of the striking members and upon an inward 25 and outward movement of the push button.

In carrying out the objects of the invention, a bell structure of any desired kind is provided, designed to have therein a base upon which a reciprocating sliding striking 30 member is arranged, which is adapted to strike against the bell upon reaching its extreme position in either direction. A bell crank lever structure is connected with the striking member and with a suitable push 35 button so as to actuate the striking member in one direction, and a spring is connected with the push button structure for giving the reverse movement for operating the striker in the opposite direction. As the 40 striker is arranged to slide in suitable ways that continuously hold the striker in a certain position at all times, the same will properly operate regardless of the position of the entire bell structure and will cause the 45 bell to ring equally well either in an upright position, inverted position, or on the side, or in fact, in any position in which it is desired to place the bell.

A practical embodiment of the invention 50 is represented in the accompanying drawings forming a part of this specification, in which similar characters of reference indicate corresponding parts in all the views.

Figure 1 is a longitudinal horizontal section through a bell and support, the bell disclosing an embodiment of the invention;

Fig. 2 is a view similar to Fig. 1, except that the same shows the push button actuated or moved to its inner position; Fig. 3 is a rear elevation of the bell with the gong 60 removed; and Fig. 4 is a section through Fig. 3 approximately on the line 4—4.

Referring to the accompanying drawings by numerals, 1 indicates a support of any kind, as for instance, a door or jamb, to 65 which the bell is adapted to be connected. The door 1 is formed with a bore 2 merging into a recessed bore 3 which accommodates a rod 4 carrying at its outer end a push button 5. The push button 5 is formed 70 with an annular flange 6 designed to engage the turned in projecting annular member 7 of the cap 8. The cap 8 is secured to the base 9 by any desired means, as for instance threads, the base 9 being in turn rigidly secured to door 1 in any desired way, as for instance by screws. On the opposite side of the door 1 to the push button 5, and associated parts, is arranged a base 10 upon which the various moving parts of the bell 75 are mounted, except rod 3 and button 5. A standard 11 is rigidly secured in any desired manner to the base 10, as for instance by being riveted thereto so as to support a gong 12, the gong 12 being removably held 80 in place by a suitable screw 13. Also preferably surrounding the standard 11 is a sleeve 85 14 for properly spacing the gong from base 10.

Rigidly secured to base 10 is a shelf or 90 bracket 15 formed with a turned down portion 16 riveted, bolted, or otherwise rigidly secured to the base 10 so as to properly support the bracket. This bracket is provided with a slot 17 for accommodating a pin 18, 95 which pin is rigidly secured to a reciprocating bar 19. The bar 19 is provided with a socket at one end in which bar 3 is loosely fitted. Intermediate its length, bar 19 is provided with an aperture for accommodating 100 the end of spring 20 so that spring 20 may continuously act on bar 19 for holding one end of the same in bore 2 of door 1, and push button 5 normally in an outer position. When the push button 5 is actuated 105 the same is actuated against the pressure of spring 20 so that when the push button 5 is released the spring will quickly return the push button to its original position, and also the bar 19 to its original position. This 110 back and forth movement of bar 19 will cause a back and forth movement of pin 18.

The pin 18 is arranged to project through a slot 21 in the bell crank lever 22 which is pivoted at 23 to the bracket 15. The opposite end of the bell crank lever to that carrying the slot 21, is provided with a pin 24 projecting through a slot 25 arranged in the striker 26. The striker 26 rests upon bracket 15 and is held in place by a partially surrounding guide 27. The guide 27 is formed with a notched out portion 28 for permitting the proper movement of pin 24 in order that pin 24 may shift the striker from the position shown in Fig. 1 to the position shown in Fig. 2. In order to hold the bar 19 correctly in position it slides or reciprocates in a suitable aperture in plate 10 and is also guided by a suitable bracket 29 riveted or otherwise secured to the bracket 15.

20 In operation, when it is desired to sound the gong, button 5 is pressed inwardly quickly. This will cause a longitudinal movement of bar 19, together with pin 18. The movement of pin 18 will move the bell crank lever 22 and thus shift the striker 26 to the position shown in Fig. 2, which will cause the gong to be sounded once. The pin 24 when bell crank lever 22 is stopped, will strike against bracket 29, but the striker 26 25 will continue to move by reason of the fact that the aperture or slot 25 is larger than the diameter of the pin. The size of the aperture 25 will also allow a certain rebound so that the gong will properly sound without 30 being damped by the striker remaining in contact therewith. Upon the release of the button 5, spring 20 will cause an actuation of the various parts for moving the striker back to substantially the position shown in 35 Fig. 1, which will cause the gong to sound a second time. The size of the aperture 25 in this instance also permits the striker to rebound and thus allow a proper sound of the gong. From this it will be seen that 40 each time the button 5 is pressed the gong will be sounded twice, and also it will be observed that the mechanism will properly operate regardless of the position of the bell so that the bell may be freely utilized in any 45 desired position.

Having thus described our invention we claim as new and desire to secure by Letters Patent:—

1. In a bell of the class described, a gong, 55 a reciprocating bar moving back and forth in a rectilinear direction, said bar acting as a striker, guides for holding said bar properly in place and permitting a proper reciprocating movement thereof, said reciprocating bar being formed with a notch or opening, a pivotally mounted bell crank lever arranged adjacent said bar, a pin rigidly secured to said bell crank lever and projecting into said notch and loosely fitting 60 therein, whereby said bell crank lever

is adapted to actuate said reciprocating bar and permit a limited free movement of said bar, said bell crank lever having a slot in the opposite arm to that carrying said pin, a reciprocating thumb operated member, a pin secured to said reciprocating thumb operated member projecting into said slot, whereby when said thumb operated member is moved said bell crank lever will be moved pivotally for actuating said striker and a spring acting on said reciprocating bar for resiliently maintaining the same in a predetermined position. 70

2. In a bell of the character described, a gong, a bar extending from near one side 80 of said gong to the other, said bar being formed with an aperture, means for securing and guiding said bar in its reciprocatory movement, a pin projecting into said aperture and loosely fitting therein, 85 whereby the bar has a movement independent of the pin, a pivotally mounted bell crank lever supporting said pin and actuating the same, a push rod structure connected with said bell crank lever for moving 90 the same and a spring for resiliently maintaining said push rod structure in a predetermined position and returning the same to said position when moved therefrom, whereby said bar may be manually operated 95 for striking one side of said gong and automatically operated by said spring for striking the opposite side of said gong.

3. In a bell of the character described, a base, a bracket upstanding from said base, 100 a gong mounted on said bracket and substantially inclosing the same, a reciprocating push rod structure moving in a plane parallel with the axis of the gong, a sliding striking bar arranged transversely of 105 said push rod structure, a bell crank lever having one of the arms loosely connected with said push rod structure and the other arm loosely connected with said bar and a spring acting on said push rod structure for 110 resiliently maintaining the same in a predetermined position, whereby when said push rod structure is manually operated said bar will strike one side of said gong and when the push rod structure is released 115 said spring will cause the bar to automatically move back to the opposite position and strike the opposite side of said gong.

4. In a bell of the class described, a gong, 120 a reciprocating bar extending from near one side of the gong to the other, the reciprocating bar having a transverse slot arranged therein, means for guiding said bar in its back and forth movement, said bar being adapted to strike alternately the opposite 125 sides of said gong, a pin extending into the slot in said bar and loosely fitting therein, whereby said bar has a limited independent movement, a pivotally mounted bell crank lever, one arm of said bell crank lever be- 130

ing rigidly secured to said pin and the other arm of said bell crank lever being formed with a slot extending longitudinally of said last mentioned arm, a reciprocating 5 operating bar extending in a direction at right angles to said first mentioned bar, a pin secured to said operating bar projecting into the slot in said bell crank lever, manually actuated means for moving said operating 10 bar in one direction and a spring for moving said operating bar in the opposite direction, whereby when said operating bar is moved manually said reciprocating bar will strike one side of said gong and when 15 released will strike the opposite side of said gong.

5. In a bell of the class described, a gong, a sliding striking bar designed to strike alternately opposite sides of said gong, means 20 for loosely connecting a bell crank lever with said sliding striking bar, an operating bar, means for loosely connecting one arm of said bell crank lever with said operating bar and a spring acting on said operating 25 bar for resiliently maintaining the same in a predetermined position whereby when said operating bar is moved manually in one direction said striking bar will strike one side of said gong and when released said 30 spring will actuate said operating bar for causing the striking bar to strike the opposite side of said gong.

6. In a bell of the class described, a gong,

a support therefor, a bracket connected with said support projecting into said gong, a 35 guide arranged adjacent said support, a reciprocating bar acting as a striker arranged in said guide and resting on said bracket, said striker being formed with a notch therein, a bell crank lever pivotally mounted 40 on said bracket having one end projecting beneath said notch, a pin rigidly secured to said bell crank lever projecting through said notch, and loosely fitting therein so as to allow a sliding free movement of said 45 striker, said bell crank lever being formed with a slot in the end opposite the end carrying said pin, a reciprocating bar arranged adjacent said bracket, a pin secured to said reciprocating bar and projecting into the 50 slot in said bell crank lever whereby when said bar is moved said bell crank lever will be moved pivotally for actuating said striker, a spring acting on said bar for resiliently maintaining the same in a predetermined 55 position, and a push button structure connected with said bar and adapted to actuate said bar against said spring.

In testimony whereof we have signed our names to this specification in the presence 60 of two subscribing witnesses.
